US00D420346S

United States Patent [19]

Hashiguchi et al.

[11] Patent Number: Des. 420,346

[45] Date of Patent: ** Feb. 8, 2000

[54] **CONTROLLER FOR VIDEO GAME MACHINE**

[75] Inventors: **Sadao Hashiguchi; Yoshihisa Nagata**, both of Kanagawa, Japan

[73] Assignee: **Hori Electric Co., Ltd.**, Yokohama, Japan

[**] Term: **14 Years**

[21] Appl. No.: **29/103,969**

[22] Filed: **Apr. 26, 1999**

[30] **Foreign Application Priority Data**

Jan. 14, 1999 [JP] Japan 11-707

[51] **LOC (7) Cl. 21-01**

[52] **U.S. Cl. D14/117.9; D14/117.9**
